UNITED STATES PATENT OFFICE.

JOHN J. WILLIAMS, OF WHEELING, WEST VIRGINIA, ASSIGNOR TO HAZEL-ATLAS GLASS COMPANY, OF WHEELING, WEST VIRGINIA, A CORPORATION OF WEST VIRGINIA.

CLOSURE CAP FOR GLASS CONTAINERS.

Application filed November 24, 1926. Serial No. 150,408.

Fig. 1 is a plan view of a vacuum seal cap embodying the invention; Fig. 2 is a view in vertical section and on an enlarged scale taken on the line 2-2 of Fig. 1 and 5 showing the cap member placed in position on the open end of a glass container of the tumbler type in readiness to be pressed into sealing relation thereto; Fig. 3 is a view similar to Fig. 2 showing the cap member 10 pressed into sealing relation to the tumbler; Fig. 4 is a view similar to Fig. 3 showing the cap member applied to a container of the glass jar, as distinguished from the tumbler, type; Fig. 5 is a view similar to Fig. 15 3 showing a sealing cap member of a modified construction; and Fig. 6 is a view in side elevation of a portion of a tumbler and the method of applying the sealing cap thereto.

20 My invention relates to caps or closure members of the type used in maintaining a vacuum seal in connection with food containers formed of glass. A closure cap of this general nature has been heretofore developed which is formed of relatively thin sheet metal having a disc-like body portion and a depending annular flange for enclosing the open end of the jar or tumbler to which the closure member is applied. A 25 feature of this structure resides in a constriction of the lower edge of the annular flange so as to form between the constricted portion and the disc or body portion of the cap an annular seat in which a rubber gasket 30 is received. In order to facilitate the placing of the cap in position on a food container without forcing the gasket out of its seat, a beveled or inclined edge is provided on the lower and inner angle of the gasket. 35 This structure is supposed to assist in causing the gasket to move into position in circumscribing relation to the open end of the container, but in actual practice the gaskets frequently buckle and are forced from their 40 seat in the capping operation. In order to overcome this objectionable feature of prior cap structures, I have provided a cap member having a similar general organization of structure with the addition that an annular seat or groove is provided in the under 45 side of the disc or body member of the cap immediately adjacent to its circumferential edge. This seat or groove serves to receive the upper edge of the gasket member and to

hold the gasket member in its place in the 55 groove provided for the purpose in the annular flange member. With this construction I have found that the gasket is retained in position during capping operations and cannot be buckled or forced inwardly out of 60 the annular position in which it is placed until the gasket has been moved into enclosing relation to the container top.

A feature of the invention resides in the 65 fact that the seat, which is thus provided for the upper edge of the gasket, is of a temporary nature only and serves to hold the gasket in position until the cap has been placed in capping relation to a jar or tumbler. In other words, the pressure which 70 is exerted on the cap member to force it into position terminates in the disappearance of the gasket holding seat by reason of the pressure exerted by the upper edge of the 75 container against the cap member immediately adjacent the inside edge of the annular seat formed in the disc or body portion of the cap. By reason of the gasket holding seat thus provided I am enabled to do away 80 with the beveled or inclined edge on the gasket member itself with the result that the whole inner superficial area of the gasket is rendered available to produce the maximum contact with the outer surface of the 85 container and thereby produce the most effective sealing action.

My invention also comprises various other features which I shall hereinafter describe and claim.

Referring to the drawings for a more detailed description of the invention, a vacuum seal cap member 10 is shown which is formed preferably of relatively thin sheet metal, the body portion having a substantially flat or disc-like formation as at 11 provided 90 with a circumscribing depending annular flange member 12 which occupies an enclosing relation to the end portion of the mouth of the tumbler or jar when the cap is in sealing relation thereto. The lower portion 95 of the flange member 12 is constricted as at 13, that is, the portion 13 has a less diameter than that of the flange member proper 12. A shoulder 14 is thus provided which forms in turn a lower edge or extremity for a recess or seat 15 provided by the inner surface 100 of the flange member 12. The seat 15 is adapted to receive a gasket member 16 which 105

is formed of rubber or other suitable material to provide sealing contact with the outer surface of the tumbler 17 when the cap is pressed into closing relation thereto.

- 6 The gasket member 16 has an annular and cylindrical conformation so that the inner surface thereof for the full width of the cylinder will have sealing contact or engagement with the outer wall surface of 10 the container with which it is used. It has been found that cap members provided with gaskets of the type shown and described can be placed in sealing relation to the mouths of the containers only with difficulty 15 because of the pronounced tendency possessed by the gasket member to buckle inwardly and be displaced from its position in contact with the inner surface of the flange 12 during the capping operation.
- 20 In order to overcome this objectionable feature of capping or sealing operations, I have provided means for preventing the buckling of the gasket member from its seat during the operation of pressing the cap 25 member into closing relation to the mouth of the container. This means takes the form of a groove or seat 18 provided in the under face of the body portion of the cap member at its juncture with the depending flange 30 member 12. The groove or seat 18 thus provided is annular in conformation and has a width such that the upper edge of the gasket member 16 fits therein and is accordingly held against radial inward movement 35 under the buckling action tending to be produced by the pressure of the upper edge of the jar or tumbler against the lower edge of the gasket in the capping operation.

The seat 18, which is thus provided for 40 engaging and holding the upper end of the gasket and thereby preventing the buckling of the gasket from its principal seat 15, is made use of only before and during the capping operation, the pressure of the capping tool 25 operating to remove the holding seat 18 from the cap structure as the cap is forced into sealed relation to the container. This results, as will be seen by a comparison of Figs. 2 and 3 of the 45 drawings, in the elimination of the seat 18 in the cap structure in the final position of the cap member shown in Fig. 3. The elimination of the seat 18 is effected by the pressure exerted by the outer edge of the 50 container 17 against the body portion 11 of the cap member immediately adjacent the seat 18.

By this arrangement, I am enabled to 55 utilize the holding seat 18 when the holding seat is needed, that is, during the capping operation. I am also enabled to utilize the full benefit of having the entire inner surface of the gasket member 16 occupy 60 contacting relation with the outer surface 65 of the container structure in order to obtain

the maximum benefit of the sealing function of the gasket member. It will be seen that the elimination of the holding seat 18 provides for the engagement of the entire inner surface of the gasket member with 70 the container structure as is clearly shown in Fig. 3 of the drawing.

While a sealing cap of the type described is particularly adapted for use with containers of the tumbler type, such as shown in 75 Figs. 2 and 3 of the drawings, this cap is equally well adapted for use with containers of the jar type, such as is shown at 19 in Fig. 4 of the drawing. This type of container is provided with annular flange or 80 rib members 20 and 21 in the portion enclosed by the flange 12 of the cap structure. In either form of the invention, the constricted portion 14 of the cap flange member 12 is so related to the container structure 85 as to be spaced slightly therefrom when the cap occupies a sealing relation to the container, thereby providing for maximum pressure of the gasket member against the 90 surface of the container to provide the required sealing effect.

In Fig. 5 of the drawing, there is shown a modified form of the invention in which the cap member 22 is provided with a reinforcing rib or bead 23 on the outer surface 95 of the flange member 24, this construction, so far as this particular feature of the cap member is concerned, following that shown in prior application, Serial No. 37,914, filed June 18th, 1925. It will be understood that 100 the cap member shown in Fig. 5 is provided with a gasket holding seat 18 as in Fig. 2, the gasket having disappeared in the capping operation by which the cap 22 was pressed into sealing relation to the container 105 17 as shown in Fig. 5.

In both forms of the cap member shown, a vacuum seal is effected, suction being applied to a receptacle containing the jar in a known manner when the cap member is 110 loosely laid on the top of the container as in Fig. 2. Following the exhausting or vacuum producing operation, the capping tool 25 is pressed downwardly to force the cap into sealing relation to the container, the temporary holding seat 18 for the gasket 115 disappearing during this operation, as has already been described.

The terms and expressions which I have 120 employed are used as terms of description and not of limitation, and I have no intention, in the use of such terms and expressions, of excluding any mechanical equivalents of the features shown and described, or portions thereof, but recognize that various structural modifications are possible 125 within the scope of the invention claimed.

What I claim is:

1. In a vacuum closure structure for containers, a cap member formed of thin, de- 130

formable material, said cap comprising a top portion and a depending flange, an annular groove formed in the under side of the top portion adjacent said depending flange, and a gasket, the upper portion of which is adapted to be received and maintained in operative position by the walls of said groove during the sealing operation, the inner face of the flange and outer face 5 of the container surrounded by said flange and the inner and outer faces of the gasket being substantially parallel to each other before and after sealing, the under face of the cap engaging the top face of the container directly and the entire sealing surface being formed by the engagement of the gasket against the plain exterior surface of the container.

2. In a vacuum closure structure for containers, a cap member formed of thin, deformable material, said cap comprising a top portion and a depending flange, an annular groove formed on the under side of the top portion adjacent its periphery, and 10 a gasket, the upper portion of which is adapted to be received and maintained in operative position by the walls of said groove during the sealing operation, said groove being adapted to be deformed to the plane 15 of the top portion during the sealing operation.

3. In a vacuum closure structure for containers, a cap member formed of thin, deformable material, said cap comprising a top portion and a depending flange, an annular groove formed on the interior of the top portion adjacent the periphery thereof, and a vertically arranged gasket adapted 20 to be received and maintained in operative position by the walls of said groove during the sealing operation, said groove being adapted to be deformed to substantially the plane of the top portion during the sealing operation.

4. In a vacuum closure structure for containers, a cap member formed of thin, deformable material, said cap comprising a top portion and a depending flange, an annular groove formed in the top portion of the cap 25 adjacent the flange, said groove being adapted to be deformed during the sealing operation, and a gasket held in said groove during application and being adapted to lie wholly outside the exterior of a container.

5. In a vacuum closure structure, a cap member formed of thin, deformable material, said cap comprising a top portion and a depending flange, an annular groove formed in the interior of the top portion adjacent the flange, said groove being adapted to receive the upper portion of a vertically arranged gasket, said groove being deformable to move the gasket into final sealing position.

6. In a vacuum closure structure, a cap 65 member formed of thin, deformable material, said cap comprising a top portion and a depending flange, means provided in the top portion to receive and position a gasket prior to complete sealing, and said means 70 being movable with relation to the top portion, during the sealing operation, to move the gasket to final sealing position.

7. The method of sealing a container with a cap which includes providing a cap of deformable material having a groove in its top portion and a gasket having one edge seated in said groove, placing the cap and gasket on the receptacle to be sealed, pressing the cap thereon, and flattening out a 75 wall of the groove to move the gasket into final sealing position.

8. The method of sealing a container with a cap which comprises seating a gasket in a groove provided in the top of a cap formed of thin, deformable material, placing the cap and gasket loosely on the receptacle, and pressing the cap on the receptacle and permanently deforming a wall of the groove 80 to move the gasket into final sealing position. 90

9. The method of sealing a container with a cap which comprises seating a gasket in a groove provided in the top of a cap formed of thin, deformable material, placing the cap and gasket loosely on the jar, extracting 95 the air from the container, and pressing the cap on the container and eliminating the groove.

10. The method of sealing containers which comprises seating a gasket in a groove 100 provided in the top of a cap formed of deformable material, and applying pressure to the cap to press simultaneously the cap on the container and flatten out a wall of the groove to move the gasket into final sealing 105 position.

11. In a vacuum closure structure for containers, a cap member formed of thin, deformable material, said cap comprising a top portion and a depending flange, an annular groove formed in the under side of the top portion adjacent said depending flange, and a gasket of initial as well as of substantially final rectangular cross-section, the upper portion of which is adapted to be received 115 and maintained in operative position by the side walls of said groove during the sealing operation, the inner face of the flange and outer face of the container surrounded by said flange and the inner and outer faces of the gasket being substantially parallel to each other before and after sealing, the under face of the cap engaging the top face of the container directly and the entire sealing surface being formed by the engagement 120 of the gasket against the plain exterior surface of the container. 125

JOHN J. WILLIAMS.
